MALVERN W. SEVERANCE, OF CLEVELAND, OHIO.

PHONOGRAPH NEEDLE AND HOLDER STRUCTURE.

1,418,478.

Specification of Letters Patent. Patented June 6, 1922.

Application filed February 24, 1921. Serial No. 447,626.

To all whom it may concern:

Be it known that I, MALVERN W. SEVERANCE, a citizen of the United States, residing at Cleveland, in the county of Cuyahoga and 5 State of Ohio, have invented certain new and useful Improvements in Phonograph Needles and Holder Structures, of which the following is a specification.

This invention relates to phonographs, 10 and particularly to the needle and needle holder therefor. More specifically, the invention relates to those types or makes of phonographs the sound box mechanism of which includes a sound box secured to the 15 tone arm, a needle receiving member or socket connected to said sound box, and a lever arm connecting said needle socket with the diaphragm of the sound box.

One type of phonograph needle now on 20 the market for the type of machine above mentioned, is made of steel, in several sizes, varying materially in length and diameter. These needles are adapted to be secured in the needle socket such as by a set screw, and 25 may be adjusted to different positions therein to vary the tone. These needles, however, have only one playing portion, the point of the needle, and when this point is worn off after playing a few records the needle is 30 worthless and must be thrown away, inasmuch as the shank of this type of needle is considerably larger than the groove in a record, so that the needle would no longer enter the groove but would ride upon the 35 ridges thereof and damage the record. Only a very few records can be played with one of these needles, necessitating the frequent changing of needles.

Another type of needle now on the market 40 comprises a metal needle holder, adapted to be secured in the needle socket, and in the end of which is solidly secured a short, fine tungsten wire or needle. This needle is very frail, having a diameter substantially equal 45 to the width of a phonograph record groove. It is therefore obvious that only a very short portion of the needle can project or extend from the end of the needle holder. While a greater number of records can be played 50 with a needle of this type, the number is necessarily limited to the extent of the needle portion projected from the holder. When this portion is worn down practically to the holder, this needle must be thrown away, as 55 the playing portion, the tungsten wire pro-

jecting from the holder, cannot be renewed.

The object of the present invention is, therefore, to provide a new and improved needle and holder structure which is adapted for use in the ordinary needle socket of any 60 of the well known makes or types of phonographs; which permits of easy and quick adjustment of the needle in its holder; and which enables a very great number of records to be played by adjustment of the 65 needle in its holder so as to replenish the playing portion of the needle as it is consumed or worn down.

Further objects of the invention are in part obvious and in part will appear more in 70 detail hereinafter.

The invention comprises the construction and arrangement of parts hereinafter described and claimed.

In the drawings, Fig. 1 is a side elevation, 75 showing the sound reproducer of an ordinary phonograph, with the needle and holder secured thereto, the needle being in playing position upon a record; and Fig. 2 is an enlarged longitudinal section of the needle and 80 holder.

Referring to the drawings, 1 represents the tone arm of an ordinary phonograph, to which is secured the usual sound box 2. 3 represents the needle receiving member or socket which is connected to the sound box in any suitable manner, such as by the ears 4. 5 represents a lever arm connecting said needle socket with the diaphragm 6 of the sound box. 7 represents my improved needle 90 holder, which is adapted to be inserted in the needle socket 3 and secured therein in any suitable manner, such as by the set screw 8. This holder may be made of any suitable material, such as brass, and comprises a cylindrical shank 9 for securement in the needle socket 3 and an enlarged head 10, the lower or bottom portion of which is flattened or cut away, as at 11, for a purpose which will later appear.

Adjustably and snugly secured in the holder 7, such as by the adjusting screw 12, is the playing needle 13, which may be made of any suitable material, such as tungsten or piano wire. This needle which is of uniform 105 cross section throughout its entire length is very fine, the diameter thereof being approximately six thousandths of an inch, substantially the width of the groove in the ordinary phonograph record.

100

105

110

It will be obvious that since the diameter of the needle throughout its entire length is substantially equal to the width of the record groove, the needle can be used without further adjustment until the portion projected from the holder has been worn down practically to the holder. The adjusting screw 12 is then unloosened and a further portion of the needle extended, thus renewing or replenishing the playing portion. This step can be repeated until practically the entire needle has been consumed or used up.

It must be borne in mind that this needle 15 13 is very frail, the diameter thereof being approximately six thousandths of an inch. It is therefore necessary that the support for the needle extend relatively close to the record being played. In order to enable the 20 needle to be thus supported, and to enable practically the entire length of the projected portion of the needle to be consumed or used up before adjustment of the needle is necessary, the lower or bottom portion of the head 25 10 is flattened or cut away, as at 11, on a horizontal line, substantially parallel with the phonograph record being played, said record being indicated at 14. It will thus be seen that the needle is supported close up to 30 the record, and that the entire projected portion of the needle, usually one-sixteenth of an inch, can be used or consumed before further adjustment of the needle is necessary.

While I have shown the needle socket 3 35 7 and the needle holder 7 as separate and distinct members, it is obvious that the needle holder may be made a unitary part of the needle socket without departing from the spirit of this invention.

40 If the playing portion of the needle should become bent or flattened in any way, such as by dropping the needle and holder, the damaged portion of the needle can be easily cut off, and a further portion of the needle extended, thus securing a new playing portion,

so that the entire needle does not have to be thrown away as is the case with needles now on the market.

The opening in the holder is substantially of the same cross section as the width of the record groove, although in the present illustration the opening throughout the shank is shown as slightly larger than that throughout the head, this variation being due merely to the use of drills of different sizes which greatly facilitate the construction of these holders.

The needles and holders may, of course, be purchased separately, so that one holder and a very few needles will last a very long time 60 and enable a very great number of records to be played.

Further advantages of the invention will be apparent to those who are skilled in the art to which it relates.

Having described my invention, I claim:

A phonograph needle and holder structure, comprising a unitary holder member provided with a substantially cylindrical shank having at one end an enlarged head, the shank of said holder member being adapted for slidable engagement in the ordinary needle socket of a sound box, said holder member being also provided with a longitudinal needle opening, the diameter thereof throughout the head being reduced from that through the shank to approximately the width of a phonograph record groove, the head of said holder member having a flattened portion extending back from the forward end of the needle opening and adapted to lie approximately parallel to the record when the needle is in operative position, a phonograph needle of uniform cross section in said opening, and a set screw in said head for adjustably securing said needle in said opening.

In testimony whereof I hereby affix my signature.

MALVERN W. SEVERANCE.
